Primary Examiner — Michael C Stout*Assistant Examiner* — Fitzgerald L Butac(74) *Attorney, Agent, or Firm* — Maginot, Moore & Beck LLP(57) **CLAIM**

The ornamental design for a non-axial turbomachine, as shown and described.

DESCRIPTION

FIG. 1 is a perspective view of a non-axial turbomachine showing our new design;

FIG. 2 is a right side elevational view of the non-axial turbomachine of FIG. 1;

FIG. 3 is a left side elevational view of the non-axial turbomachine of FIG. 1;

FIG. 4 is a front side elevational view of the non-axial turbomachine of FIG. 1;

FIG. 5 is a rear side elevational view of the non-axial turbomachine of FIG. 1;

FIG. 6 is a top plan view of the non-axial turbomachine of FIG. 1; and,

FIG. 7 is a bottom plan view of the non-axial turbomachine of FIG. 1.

The broken lines shown in the drawings illustrate portions of the non-axial turbomachine that form no part of the claimed design.
